SANITARY TOILET SEAT COVER
DISPENSING MACHINE

Nicholas Altieri, Philadelphia, Pa.

Application January 27, 1938, Serial No. 187,308

2 Claims. (Cl. 4—247)

This invention relates to sanitary toilet seat cover dispensing machines particularly adapted for public lavatories.

It is an object of the invention to provide a mechanism associated with a toilet bowl including a continuous strip of individual seat covers adapted to be moved across the seat of the toilet and supply a clean cover for the seat upon each operation of the machine.

10 A further object of the invention resides in providing a coin controlled mechanism for moving the continuous strip of seat covers a predetermined distance upon each operation of the mechanism and arresting the movement of the strip to properly align the individual seat covers with the seat of the toilet.

15 Another object of the invention resides in providing a mechanism of the above-mentioned character which is simple and durable in construction, attractive in appearance, reliable and efficient in operation and inexpensive to manufacture.

Other objects and advantages of the invention will be apparent during the course of the following description.

In the accompanying drawings, forming a part of this specification and in which like numerals are employed to designate like parts throughout the same:

30 Fig. 1 is a perspective view of the machine installed in a lavatory.

Fig. 2 is a front view of the machine with the front wall removed,

Fig. 3 is a section taken on line 3—3 of Fig. 2,

Fig. 4 is a section taken on line 4—4 of Fig. 2,

Fig. 5 is a section taken on line 5—5 of Fig. 2, and,

Fig. 6 is a section taken on line 6—6 of Fig. 4.

In the drawings, wherein for the purpose of illustration, I have shown a preferred embodiment of my invention, the numeral 5 denotes a metal cabinet built around the toilet bowl 6 with an opening 7 in the top wall, in register with the toilet seat 8. A continuous strip of individual seat covers 9 is adapted to move across the top of the toilet seat 8, the same being constructed of paper or other suitable material. The seat covers 9 are supplied to the machine in roll wound on a spool 10 which is journaled in brackets 11 and 12, at one side of the toilet bowl near the bottom of the cabinet. The bracket 12 is slidably mounted in the base 13 so that it may be moved outwardly to permit removal of the spool 10 to replenish the supply of seat covers when necessary. The strip of covers pass upwardly from

the spool 10 between the vertical parallel guide plates 14 and over the guide roller 15 journaled in brackets 15' suspended from the top of the cabinet on a horizontal plane with the level of the toilet seat. The strip passes across the top 6 of the toilet seat and is trained over the guide roller 16 mounted in brackets 16' suspended from the top of the cabinet on the opposite side of the bowl, passing down between the vertical parallel guide plates 17 with its free end connected to 10 the spool 18 which is rotated by a spring motor 19, to wind the strip of covers on the spool 18, as the strip unwinds from the spool 10. The spring motor 19 consists of a casing 20 attached to the rear wall of the cabinet having a coil 15 spring 21 disposed therein, one end of the spring being attached to the periphery of the casing, as at 22, while the opposite end is attached to the rotatable bearing 23 having a socket to receive one end of the spool shaft 24, the opposite end 20 of the shaft being mounted in the bracket 25 slidably mounted in the base 26, which permits removal of the spool when desired. A crank 27 is adapted to be attached to the free end of the shaft 24 for rotating the shaft to wind the spring 25 of the spring motor before attaching the strip of covers to the spool 18.

The movement of the continuous strip of covers is controlled by stop pins 28 carried by the plate 29 extending transversely of the strip. The pins 30 project from the plate 29 adjacent its upper edge and engage the marginal edges of the strip, for entering the openings 30 formed at spaced intervals throughout the length of the strip. The pins are projected into the openings by springs 35 mounted thereon and each of the openings are suitably reinforced to prevent tearing. Brake shoes 32 are adapted to engage the peripheries of the spool flanges being carried by rods 33 supported by the plate 29, adjacent its lower edge 40 and springs 34 mounted on the rods 33 normally hold the brake shoes in applied position. A rod 35 extends from the center of plate 29 which extends through an opening 36 in the upstanding bracket 37 attached to the bottom of the cabinet 45 and a spring 38 mounted on the rod 35 between the plate 29 and bracket 37 normally urges the plate 29 in the direction of the strip. The bracket 37 also carries guide pins 37' on opposite sides of the rod 35 which project through openings in the plate 29 and springs 38' carried by the guide pins urge the plate to operating position. The free end of the rod 35 is bent upwardly and flattened to form a tongue 39 which engages the teeth of the star wheel 40 mounted on the shaft 55.

41 journaled in the bearings 42 formed integral with the bracket 37. The spool 10 has associated therewith brake shoes 43 and stop pins 44 carried by a plate 45 and a bolt 46 extending from the center of plate 45 is slidably supported by an upstanding bracket 47, the free end of the bolt 46 being engaged by the teeth of a star wheel 48 mounted on a shaft 49 supported by the bracket 50. A spring 51 mounted on the bolt 46 between the plate 45 and bracket 47 normally urges the plate towards the strip and springs 52 normally hold the brake shoes in engagement with the peripheries of the spool flanges, while springs 53 project the stop pins 44 into engagement with the marginal edges of the strip. Guide pins 53' project from bracket 47 through openings in the plate 45 and carry springs 54' which urge the plate to operative position. The shafts 41 and 49 at one end are equipped with pulleys 54 and 55 connected by a crossed belt 56, so that movement of the shaft 41 is imparted to the shaft 49, for simultaneously releasing and stopping the movement of the strip at points adjacent each of the spools 10 and 18.

25 The star wheel 40 is actuated by a reciprocating bar 57 slidably mounted in a bracket 58 attached to the end wall of the cabinet having a pawl 59 pivotally attached to the lower end of the bar for movement in one direction only. A spring 60 having one end attached to the pawl and its opposite end to the cabinet normally holds the pawl in position for operative engagement with the teeth of the star wheel on upward movement of the bar 57, but permits the pawl 35 to fold against the bar and pass the teeth of the star wheel on downward movement of the bar. A cable 61 is attached to the upper end of the bar 57 and passes through a conduit 62 extending between the cabinet and box 63 housing the coin controlled mechanism for operating the cable. The upper end of the cable 61 is trained over the guide pulley 64 and is attached to the swinging lever 65 pivotally attached at one end to the rear wall of the box 63, as at 66. The free end of the lever 65 is bent at right angles and extends through the arcuate slot 67 in the front wall of the box to provide an operating handle 68 for the lever. A spring 69 normally holds the lever 65 in its starting position and a hook 70 extending laterally from the lever 65 is normally engaged by the pivoted latch bar 71 which locks the lever 65 in its starting position. The latch bar 71 is pivotally mounted intermediate its ends, as at 72, the free end of the bar being disposed within the lower end of the coin chute 73 in the path of the coin. The coin chute is pivotally mounted in the box 63 by a pivot pin 74 and is normally held in alignment with the coin slot 75 and end of the latch bar by a spring 76. A cable 77 having one end attached to the lower end of the coin chute is trained over guide pulleys 78 and 79 having its opposite end attached to the lever 65, so that upon movement of the lever 65, the coin chute is swung into alignment with the coin receptacle 80 for depositing the coin therein.

In order to disinfect the strip of covers before and after using, a spray 81 is mounted adjacent the strip on each side of the toilet bowl, being connected by conduits 82 with the germicide holding receptacle 83 attached to the back wall of the cabinet, the germicide being discharged from the receptacle by a pump plunger 84 connected to the arm 85 attached to the shaft 86 mounted in brackets 87, the free end of the shaft having a

crank arm 88 attached thereto which is disposed in the path of movement of the teeth of the star wheel 40. Upon rotation of the star wheel the pump plunger is actuated to discharge the germicide from the sprays 81 onto the surface of the strip. The receptacle 83 receives its supply of germicide from the container 88' through the conduit 89'. A register 89 is mounted adjacent the front wall of the cabinet being supported by the bracket 90 attached to the end wall, so as to be visible through the opening 91 in the front wall. The register denotes the number of seat covers remaining on the roll and is operated by a chain of belt gearing 92 which is connected by a belt 93 with the pulley 94 on the end of the shaft 41.

In operation, the spool 10 containing the roll of seat covers 9 is mounted in its brackets in the cabinet and the strip of covers is then trained over the toilet seat 8 and connected to the spool 18, 20 after the spring motor 19 has been wound by turning the crank 21. With the control mechanism in the position shown in Fig. 2, the stop pins 28 and 44 will be engaged with the openings 30 in the marginal edges of the strip 9 and the 25 brake shoes 32 and 43 will be set against the peripheries of the flanges of spools 10 and 18, thus arresting the movement of the strip. Upon insertion of a coin in the slot 75, the coin will drop in the coin chute 73 and rest on the end of the 30 latch lever 71, thereby causing the latch lever to rock on its pivot 72 and become disengaged from the hook 70. The lever 65 is then moved by the handle 68, which allows the rod 57 to move downwardly under the action of the spring 60 and at 35 the same time pull the cable 71 which swings the coin chute 73 away from the latch rod, so that the coin is discharged into the coin receptacle 80. On return movement of the lever 65, the rod 57 is pulled upwardly causing the pawl 59 to engage 40 with a tooth of the star wheel 40 thereby turning the shaft 41 which through the belt 56 imparts a corresponding movement to the shaft 49 on which is mounted the star wheel 48. As the star wheels 40 and 48 turn, the rods 35 and 46 are retracted 45 by engagement of one tooth of the wheels with the upturned ends of the rods, thereby releasing the brake shoes 32 and 43 and retracting the pins 28 and 44 from the openings 30, so that under the action of the spring motor 19 the spools 18 and 50 10 are free to revolve moving the strip 9 across the toilet seat and bring a clean cover into register with the seat. The star wheels only move the rods 35 and 46 a sufficient distance to release the stop pins from the holes 30 and then immediately releases the rods so that the pins return under the action of springs 31 and 53 into position for engagement with the next holes 30 of the strip. At the same time the strip is moved, the pump 83 is actuated to discharge a germicide 60 through the sprays 81 onto the surface of the strip, to disinfect the used and clean covers. The register 89 denotes to the user the number of covers remaining on the roll.

It is to be understood that the form of my invention herein shown and described is to be taken as a preferred example of the same and that certain changes in the shape, size and arrangement of the parts may be made without departing from the spirit of the invention or the scope of the subjoined claims.

Having thus described my invention, I claim:

1. In a toilet seat cover dispensing apparatus, the combination with a toilet bowl, of a pair of spools rotatably mounted on opposite sides of 75

the toilet bowl, a continuous strip of seat covers connected to said spools and trained over the seat of the toilet bowl. A spring motor for rotating one of said spools to wind the strip thereon, stop pins engageable with openings in said strip for arresting the movement of said strip, brake shoes for engaging the flanges of said spools, movable supporting means for said stop pins and brake shoes, means for moving said supporting means to simultaneously retract said pins and brake shoes and manual means for operating said last mentioned means.

2. In a toilet seat cover dispensing apparatus, the combination with a toilet bowl, of a pair of spools rotatably mounted on opposite sides of the toilet bowl, a continuous strip of seat covers con-

nected to said spools and trained over the seat of the toilet bowl, a spring motor for rotating one of said spools to wind the strip thereon, stop pins engageable with openings in said strip for arresting the movement of said strip, movable supporting means for said stop pins, a rotatable star wheel operable to engage said movable supporting means and retract said pins to release said strip, a reciprocating bar for operating said star wheel, a hand lever for actuating said reciprocating bar, a germicide spraying mechanism operated by said star wheel for spraying said strip and a coin controlled mechanism for locking and releasing said hand lever.
